UNITED STATES PATENT OFFICE

ERWIN HOFFA AND ERWIN THOMA, OF FRANKFORT-ON-THE-MAIN, GERMANY, ASSIGNEES TO GENERAL ANILINE WORKS, INC., OF NEW YORK, N. Y., A CORPORATION OF DELAWARE

BLUE TO VIOLET-BLUE WATER-INSOLUBLE AZO-DYESTUFFS

No Drawing. Application filed December 5, 1930, Serial No. 500,421, and in Germany October 17, 1928.

The present invention relates to blue to violet-blue water-insoluble azo-dyestuffs.

This application is a continuation in part application to our co-pending U. S. application Ser. No. 302,486, filed September 13, 1929.

We have found that dyestuffs of valuable dyeing properties and yielding blue to violet tints are obtainable by coupling with 10 a 2,3-hydroxynaphthoylarylamine a diazo compound of a compound of the following general formula:

15 wherein at least one R stands for a naphthalene residue which may be substituted and the other R stands for an aromatic residue which may be substituted, which residues, however, must not contain substituents rendering the products soluble in water.

The shades are varying within wide limits; reddish-violet to deep, blackish-blue tints are obtained according to the selection of the components.

20 The dyestuffs obtainable according to the present invention correspond to the following general formula:

35 wherein at least one R stands for a naphthalene residue which may be substituted and the other R stands for an aromatic residue which may be substituted, aryl for an aryl residue which may be substituted.

The following examples serve to illustrate 40 our invention, but they are not intended to limit to thereto; the parts being by weight:

(1) 2.8 grams of diazonium chloride obtained from 4-amino-phenyl-beta-naphthylamine are made into a paste with water the whole being made up with cold water to

1 liter. Before dyeing 1 gram of sodium bicarbonate is added to the solution. In this solution there are dyed for half an hour 50 grams of cotton yarn which have been impregnated with a solution containing per 50 liter 6 grams of 2,3-hydroxynaphthoic acid-anilide, 12 grams of sodium Turkey red oil of 50 per cent. strength, 9 grams of caustic soda solution of 28 per cent. strength, 6 grams of formaldehyde of 40 per cent. 55 strength. After the development, the yarn is wrung out, well washed and treated in a hot soap bath. The dyeing thus obtained has a deep navy-blue shade with a red hue and good fastness properties. 60

(2) By substituting in Example 1 for the 2.8 grams of the diazonium chloride, 3.3 grams of diazonium chloride from 4-amino-phenyl-2-carboxylic acid-methyl-ester-beta-naphthylamine and padding the material 65 with a solution containing 4 grams of 2,3-hydroxynaphthoic acid-4'-chloro-1'-anilide, 8 grams of sodium Turkey red oil of 50 per cent. strength, 8 grams of caustic soda solution of 28 per cent. strength, 4 grams of 70 formaldehyde of 40 per cent. strength, per liter, there is obtained a very dull reddish dark-blue dyeing of good fastness to washing and kier-boiling.

(3) Well boiled and dried cotton yarn is 75 impregnated with a solution containing per liter 4 grams of 2,3-hydroxynaphthoic acid-4'-chloro-1'-anilide, 8 grams of caustic soda solution of 28 per cent. strength and 10 grams of Turkey red oil of 50 per cent. 80 strength, thoroughly wrung out, developed in a diazo solution which has been neutralized with sodium bicarbonate and which contains 2.7 grams of 4-amino-3-chloro-phenylbeta-naphthylamine per liter, rinsed 85 and soaped for half an hour at boiling temperature. Thus a dark-blue dyeing is obtained.

(4) A dyestuff can be obtained in the same manner by using the diazo compound from 90

4-amino-3,5-dichloro-phenyl-beta-naphthyl-amine.

The following examples serve to furthermore illustrate the invention:

5	Diazo component	Grounding liquor	Dyeing
	4-aminophenyl-1'-aminonaphthalene.	2,3-hydroxynaphthoyl-3'-nitro-1'-aniline.	Middle blue
10	4-aminophenyl-2-carboxylic acid-methylester-1'-naphthylamine.	-4'-chloro-2'-methy1-1'-aniline.	Very reddish-blue.
	4-aminophenyl-1'-amino-4'-ethoxynaphthalene.	-1'-aniline.	Dark reddish-blue
	4-amino-1,1'-dinaphthyl-amine.	-1'-aniline.	Dark reddish-violet
	1-amino-4-(4'-ethoxy-phenyl-amino)-naphthalene.	-1'-aniline.	Very reddish-violet
15	4-aminophenyl-2'-amino-6'-methoxy-naphthalene.	-4'-chloro-1'-aniline.	Greenish-blue
	4-aminophenyl-2'-amino-7'-methoxy-naphthalene.	-4'-chloro-1'-aniline.	Reddish-blue
	4-aminophenyl-1'-amino-4'-methoxy-naphthalene.	-4'-chloro-1'-aniline.	Navy blue
	4-aminophenyl-2'-amino-6'-methoxy-naphthalene.	- β -naphthyl-amine.	Greenish-blue

20 Instead of producing the dyestuffs on the fiber as indicated in the preceding examples they can also be produced in substance or on any of the usual substrata which are adapted for the production of lakes and isolated in a suitable manner.

30 Since an object of the present invention is to provide dyestuffs of good fastness properties, which dyestuffs are insoluble in water and alkalies, it is to be understood that the aromatic nuclei of the general formulae appearing in the appended claims contain no substituents as are known to render organic compounds soluble in water or alkalies and to tend to depreciate the fastness of the dyestuffs to alkalies. Substituents of this kind are, for instance, the sulfonic acid and the carboxylic acid group.

35 We claim:

40 1. As new products, the dyestuffs of the following general formula:

50 wherein at least one R stands for a residue of the naphthalene series, the other R for a residue of the benzene or naphthalene series and Z for a residue of the benzene or naphthalene series, the said dyestuffs being insoluble in water and yielding when produced on the fiber dyeings the shades of which 55 vary from reddish-violet to deep blackish-blue.

55 2. As new products, the dyestuffs of the following general formula:

65 wherein R₁ stands for a residue of the naphthalene series, R₂ for a residue of the

benzene or naphthalene series and Z for a residue of the benzene or naphthalene series, the said dyestuffs being insoluble in water and yielding when produced on the fiber dyeings the shades of which vary from reddish-violet to deep blackish-blue.

70 3. As new products, the dyestuffs of the following general formula:

80 wherein R₁ stands for a naphthalene residue which may be substituted by alkoxy groups, R₂ stands for a benzene residue which may be substituted by COO-alkyl or halogen and Z stands for a residue of the benzene or naphthalene series, the said dyestuffs being insoluble in water and yielding when produced on the fiber dyeings the shades of which vary from reddish-violet to 85 deep blackish-blue.

85 4. As new products, the dyestuffs of the following general formula:

95 wherein R₁ stands for a naphthalene residue which may be substituted by alkoxy groups, R₂ for a benzene residue which may be substituted by COO-alkyl or halogen and Z for a benzene residue which may be substituted by alkyl, halogen or nitro groups, the said dyestuffs being insoluble in water and yielding when produced on the fiber dyeings the shades of which vary from reddish-violet to deep blackish-blue.

100 5. As a new product, the dyestuff of the following probable formula:

115 which is insoluble in water and yields when produced on the fiber a dyeing, the shade of which is a deep navy blue with a red hue.

120 6. As a new product, the dyestuff of the following probable formula:

130 which is insoluble in water and yields when produced on the fiber a dyeing, the shade of which is a middle blue.

7. As a new product, the dyestuff of the following probable formula:

10 which is insoluble in water and yields when produced on the fiber a dyeing, the shade of which is a very reddish-violet.

8. Fiber dyed with the dyestuff as claimed in claim 1.
